UNITED STATES PATENT OFFICE.

JAMES H. W. MARRIOTT, OF WASHINGTON, DISTRICT OF COLUMBIA.

SUPPORTING-TABLE AND ATTACHMENT FOR TYPE-WRITERS.

SPECIFICATION forming part of Letters Patent No. 759,820, dated May 10, 1904.

Application filed November 10, 1903. Serial No. 180,539. (No model.)

To all whom it may concern:

Be it known that I, JAMES H. W. MARRIOTT, a citizen of the United States, residing at Washington, in the District of Columbia, have 5 invented certain new and useful Improvements in Supporting-Tables and Attachments for Type-Writers, of which the following is a specification.

The purpose of my invention is to provide a 10 supporting-table for type-writing machines adapted to write upon flat surfaces in which the machine is supported upon tracks or ways at a fixed distance above the writing-surface; and it includes means for supporting a movable platen at the proper height to receive a 15 the impressions of the type and also means for holding a book with the page to be printed upon at the proper height to receive the impressions of the type and for clamping the 20 pages of the book firmly together, so that the book-pages may be written upon without the use of a platen arranged between the pages.

In the accompanying drawings, Figure 1 is a 25 top plan view of the writing-machine table with the cover removed, showing a book arranged upon the adjustable book-support beneath the clamping-frame and the guideways for the writing-machine. Fig. 2 is a central transverse section through the upper portion 30 of the supporting frame or table on the line 2 2 of Fig. 1, the adjustable book-support and clamping-frame being shown in side view. Fig. 3 is a top perspective view of the clamping-frame. Fig. 4 is a top plan view of the 35 supporting-table having the machine-guideways attached with the cover carrying the platen-guideways arranged upon the table and the platen-carriage and platen upon the guideways, and Fig. 5 is a section on the line 40 5 5 of Fig. 4.

Referring to Figs. 1, 2, and 3 of the drawings, A indicates the body of the frame or casing which supports the writing-machine and the various devices for holding a book or 45 sheet of paper at the proper height relatively to the machine to receive the impressions of the type. This frame or casing, as shown in Figs. 1 and 2, has vertical front and rear walls 1 and 2, respectively, parallel with one

another, and parallel end walls 3 and 4, the 50 upper portion of the casing being oblong and rectangular in top plan view, as shown. A pair of parallel guideways 5 and 6 are arranged transversely of the supporting table or casing at a fixed height above the upper 55 edges of its walls, these guideways, as shown, being supported by standards 7, which are secured to the rear side of the supporting frame or casing. Within the interior of the casing is arranged a rectangular book-support 60 8, fitting closely against the walls of the casing and having a flat upper surface. This book-support may be adjusted vertically by any suitable means. In the drawings the book-support is secured at its center to a vertical screw 9, upon which is journaled a worm-wheel 10. The worm-wheel is arranged within an opening 11 in a supporting-bar 12, which latter is secured at its ends to the walls of the casing and supports the worm-wheel, the latter in turn supporting the screw and the book-support. The book-support may be raised and lowered by means of a hand-wheel 13 upon a worm-shaft 14, having a worm 15, which engages the teeth on the worm-wheel. 75

As the writing-machine guideways are held rigidly in a horizontal position, it is necessary in order to effect proper printing to maintain the page of the book B, which is to be written upon, at a fixed distance below the 80 level of the machine-guideways. For this purpose I provide a flat clamping-frame C, having a rectangular central opening 16 of sufficient length and width to expose the area upon the book-leaf where it is desired to print. The side bars 17 and cross-bars 18 rest upon the sides and ends of the page, respectively, when in position. Gage-pins or projections 19 are secured to the corners of the clamping-plate and project vertically downward from 85 its under side. The lower ends of these pins, as shown in Fig. 2, are adapted to rest upon the upper edges of the walls of the casing, and these gages support the clamping-plate at the proper height relatively to the machine-guideways, so that when the book is forced upward by the book-support against the under side of 90 the clamping-plate the page of the book will 95

be firmly held at exactly the proper distance from the impression-point of the writing-machine. In order to hold the clamping-plate firmly against the book, latches 20 are provided at each end of the clamping-plate, and these latches engage hasps 21, secured to the front and rear walls of the casing. The upward pressure of the book-support compresses the leaves of the book, so that they form a sufficiently firm printing-bed, and it is unnecessary to use a platen beneath the page which is being written upon. This device for readily setting and holding the page of a book at a fixed distance from the writing-machine is designed particularly for use in connection with a machine such as shown in my application, Serial No. 148,611, filed March 19, 1903, in which the writing-machine is movable toward and from the operator, and a platen is also movable toward and from the operator. In writing upon heavy books the machine is thus adjustable for line-spacing; but in writing upon bill-heads or other light detached papers it is of advantage to allow the machine to remain stationary and move the platen for line-spacing, as this leaves the writing-machine always at the same distance from the operator and the work becomes less irksome. In order to provide a supporting-table suitable for both purposes, the clamping-frame referred to is made detachable from the supporting-table and a cover D (shown in Figs. 4 and 5) is provided, which cover when in position rests upon the upper edges of the casing and is secured in position by dowel-pins 22, secured to the cover and entering suitable openings in the upper edges of the casing. Upon this cover are arranged platen-guideways 23 and 24, extending parallel with one another and transversely of the cover. Upon these guideways is arranged a platen-carriage 25, consisting of a light metal frame, and a platen 26 rests upon the platen-carriage. The platen-carriage is provided with a rack-bar 27, and suitable mechanism 28, arranged upon the cover D, is provided for spacing the platen rearwardly along the platen guide-rails for line-spacing. The platen-carriage, removable platen 26, and spacing mechanism form the subject of my pending application, Serial No. 175,773, and need not here be particularly described. The upper surface of the printing-bed 26^a of the platen is when in position at the same height or distance above the upper edges of the casing as the page of a book when the latter is pressed against the under side of the clamping-plate C in Fig. 2, so that it is at the exact height for receiving the impressions of the type from the machine, which travels on the fixed machine-guideways 5 and 6. The platen-carriage may be omitted, and a platen provided with a rack may be spaced along the platen-guideways, in which event it will of

course be necessary to raise the platen to the desired height by increasing the height of the rails or the height of the cover above the edges of the casing.

It will be seen from the foregoing description that with my improvements the supporting-table may be arranged for bookwork or for lighter work admitting of platen-spacing in a few moments.

Having described my invention, what I claim, and desire to secure by Letters Patent, is—

1. The combination with a supporting table or casing having a removable platen-supporting device, of a vertically-adjustable book-support within the casing, a removable clamping-frame adapted to rest upon the casing and to extend over said book-support when the platen-supporting device is removed, means for securing said frame against upward movement relatively to the casing, and a pair of machine-guideways rigidly secured to said casing and extending horizontally at a fixed distance above the lower side of said clamping-frame.

2. The combination with a supporting table or casing having a removable cover provided with platen-guideways, of a vertically-adjustable book-support within the casing, a removable clamping-frame adapted to rest upon the casing and to extend over said book-support when the cover is removed, means for securing said frame against upward movement relatively to the casing, and a pair of machine-guideways rigidly secured to said casing and extending horizontally at a fixed distance above the lower side of said clamping-frame.

3. The combination with a supporting table or casing and machine-guideways supported above the casing, of a clamping-frame arranged transversely of the casing, and having gage-pieces resting upon the casing and adapted to support the clamping-frame with its lower side at a fixed distance from the guide-rails, and a vertically-adjustable book-support below said clamping-frame.

4. The combination with a supporting table or casing and machine-guideways supported above the casing, of a clamping-frame arranged transversely of the casing and having gage-pieces resting upon the casing and adapted to support the clamping-frame with its lower side at a fixed distance from the guide-rails, means for removably securing said frame to the casing, and a vertically-adjustable book-support below said clamping-frame.

5. The combination with a supporting table or casing having a removable cover and machine-guideways supported horizontally above the casing, of a clamping-frame having gage-pieces adapted to rest on the upper walls of the casing and to support said frame with its lower side at a fixed distance from the machine-guideways, means for securing said

frame to the casing, and a vertically-adjustable book-support within the casing.

6. The combination with a supporting table or casing having a removable cover provided 5 with platen-guideways, and machine-guideways supported horizontally above the casing, of a clamping - frame having gage - pieces adapted to rest on the upper walls of the casing when the cover is removed and to support 10 said frame with its lower side at a fixed distance from the machine-guideways, means for securing said frame to the casing, and a vertically-adjustable book - support within the casing.

15 7. The combination with a table or casing, and machine - guideways supported thereby above the casing, of a vertically-adjustable book-support within the casing, a clamping-frame above said book-support having gage 20 pins or pieces adapted to rest upon the casing and to support the clamping-frame with its lower side at a fixed distance from the machine-guideways, said frame having side bars adapt-

ed to rest upon the lateral edges of a book-page, and means for securing said frame to the 25 casing.

8. The combination with a table or casing, and machine - guideways supported thereby above the casing, of a vertically-adjustable book-support within the casing, a clamping- 30 frame above said book-support having gage pins or pieces adapted to rest upon the casing and to support the clamping-frame with its lower side at a fixed distance from the machine-guideways, said frame having side bars 35 adapted to rest upon the lateral edges of a book-page, and cross-bars adapted to rest on the upper and lower edges of the page, and means for securing said frame to the casing.

In testimony whereof I affix my signature in 40 presence of two witnesses.
